UNITED STATES PATENT OFFICE.

FRED A. HAUSE, OF NORTH BESSEMER, PENNSYLVANIA.

PADDLE.

1,233,876.

Specification of Letters Patent. Patented July 17, 1917.

Application filed January 4, 1917. Serial No. 140,507.

To all whom it may concern:

Be it known that I, FRED A. HAUSE, a citizen of the United States of America, residing at North Bessemer, county of Allegheny, and State of Pennsylvania, have invented certain new and useful Improvements in Paddles, of which the following is a specification.

This invention relates to paddles for 10 pelling canoes and boats and has for its object the provision of a paddle for such purposes, in a manner as hereinafter set forth, with a sectional handle to provide for the convenient handling, carrying and storing of the paddle when not in use.

A further object of the invention is to provide, in a manner as hereinafter set forth, a paddle with a sectional handle, and with the sections of the handle capable of 20 being shifted to locking engagement with each other, to prevent the separation of the handle sections when the paddle is used.

Further objects of the invention are to provide a paddle for the purpose set forth 25 which is simple in its construction and arrangement, strong, durable, efficient in its use, readily assembled and inexpensive to manufacture.

With the foregoing and other objects in 30 view the invention consists of the novel construction, combination and arrangement of parts, as hereinafter more specifically described and illustrated in the accompanying drawings, wherein is shown an embodiment 35 of the invention, but it is to be understood that changes, variations and modifications can be resorted to which come within the scope of the claims hereunto appended.

In the drawings wherein like refer- 40 ence characters denote corresponding parts throughout the several views:

Figure 1 is an elevation of a paddle in accordance with this invention.

Fig. 2 is a section on line 11—11, Fig. 1.

Fig. 3 is a section on line 111—111, Fig. 2.

Fig. 4 is a longitudinal sectional view illustrating a modified form of lock between the handle sections.

Referring to Figs. 1, 2 and 3 of the drawings 50 1 denotes the blade and 2 and 3 the sections of the handle. The handle section 2 is an integral portion of the blade 1 and its free end is reduced as at 4 to provide a shoulder 5.

Mounted upon the reduced end 4, of the section 2, is a sleeve 6, which at one end

abuts against the shoulder 5, and at its other projects beyond the free terminus of the reduced end 4. The sleeve 6 intermediate its ends is formed with an opening 7 for a purpose to be presently referred to, and said sleeve 6 is secured to the reduced end 4, by a connecting element 8, in the form of a transversely extending rivet.

The handle section 3 has a head 9 at one 65 end and has its other end reduced to provide a cylindrical extension 10, a tapering tongue or tenon 11, and a shoulder 12.

Mounted on the extension 10 and abutting against the shoulder 12, is a sleeve 13, provided at its inner end with a flange 14. The sleeve 13 at one end is flush with the free 70 end of the extension 10, and said sleeve 13 is secured to the extension 10, by a connecting element 15, in the form of a transversely 75 extending rivet.

The extension 10 has a peripheral longitudinal groove 16, with the bottom thereof inclining downwardly from the inner toward the outer end of said extension 10. 80

Arranged within the sleeve 13 is a longitudinal flat spring 17, which has its rear end secured by a rivet 18^a to the flanged end of the sleeve 13. The forward end of the spring 17, has a lateral lug 18, which 85 projects through an opening 19, formed in the sleeve 13. The groove 16 permits of the inward shifting of the spring 17 with respect to the extension 10.

The reduced end 4 of the handle section 90 2, has a socket 20 for the reception of the tongue 11, when the handle sections are coupled together.

The diameter of the sleeve 13, with respect to the inner diameter of the sleeve 6, is 95 such that the sleeve 13 will snugly fit the inner face of the sleeve 6, to set up a frictional clamp between said sleeves when the handle sections are connected together.

When the handle sections are coupled together the sleeve 6 is inclosed by the sleeve 13, and abuts against the flange 14. The sleeve 6 is shifted so that its opening 19 will register with the opening 7, in the sleeve 13, whereby the lug 18 will project through the opening 7 and the handle sections will be coupled together.

The spring 17, lug 18, openings 7 and 19 set up a latching device for coupling the handle sections together.

Referring to Fig. 4 the handle section carried by the blade is indicated at 21 and the

other handle section at 22. The section 21 is reduced to provide a cylindrical extension 23, providing a shoulder 24, and mounted on the extension 23, is a sleeve 25, having a 5 peripheral flange 26, at one end. The sleeve 25 abuts against the shoulder 24 and is secured to the extension 23 by a rivet 27. The sleeve 25 is flush at its outer end with the free end of the extension 23, and the latter 10 has a peripheral longitudinal groove 28, with the bottom thereof inclining downwardly from its inner toward its outer end.

Arranged within the sleeve 25 is a longitudinal flat spring 29, which has its inner 15 end secured by a rivet 30, to the flanged end of said sleeve. The outer end of the spring 29, has a lateral lug 31, which projects through an opening 32, in the sleeve 25. The groove 28 permits of the inward shifting of 20 the spring 29 with respect to the extension 23.

The handle section 22 has a reduced end 33, to provide a shoulder 34, and mounted on said end 33 is a sleeve 35, which at one end 25 abuts against the shoulder 34, and at its other end projects beyond the free terminus of the end 33. The sleeve 35, intermediate its ends has an opening 36. The sleeve 35 is connected to the section 22 by a rivet 37. 30 The diameter of the sleeve 25, with respect to the inner diameter of the sleeve 35, is such that the sleeve 25 will snugly fit the inner face of the sleeve 35 to set up a frictional clamp between said sleeves when the 35 handle sections are coupled together.

When the handle sections 21 and 22 are connected together the sleeve 35 incloses the sleeve 25, and abuts against the flange 26. The sleeve 35 is shifted so that the opening 40 36, will register with the opening 32, whereby the lug 31, will project through the opening 36 and the handle sections will be coupled to each other. The spring 29, and lug 31, with openings 32, and 36, provide a latching 45 device for the handle sections.

What I claim is:—

1. A paddle having a pair of handle sections, one of said sections having an extension provided with a peripheral groove, a 50 flanged sleeve inclosing said extension and having an opening, a latching element arranged in the sleeve and including a lug projecting through said opening, said groove providing a clearance for the shifting of 55 said element, and a sleeve carried by the other handle section and inclosing the flanged sleeve and abutting against the

flange thereof, said second sleeve having an opening capable of registering with the opening in the flanged sleeve to receive said 60 lug to couple the handle sections.

2. A paddle having a pair of handle sections, one of said sections having an extension provided with a peripheral groove, a 65 flanged sleeve inclosing said extension and having an opening, a latching element arranged in the sleeve and including a lug projecting through said opening, said groove providing a clearance for the shifting of 70 said element, and a sleeve carried by the other handle section and inclosing the flanged sleeve and abutting against the flange thereof, said second sleeve having an opening capable of registering with the opening in the flanged sleeve to receive said 75 lug to couple the handle sections, said extension having a tongue, and said other handle section having a socket for the reception of the tongue when the handle sections are coupled. 80

3. A paddle having a pair of handle sections, one of which has secured therewith a flanged sleeve and the other a sleeve adapted to inclose the flanged sleeve and abut against the flange thereof, and latching means carried by one of said sleeves, extending through the body thereof and further adapted to project through the body of the other sleeve for connecting the handle sections together, and one of said sections provided with means to form a clearance for the operation of said latching means. 85

4. A paddle having a pair of handle sections, one of which has secured therewith a flanged sleeve and the other a sleeve adapted 90 to inclose the flanged sleeve and abut against the flange thereof, and latching means carried by one of said sleeves, extending through the body thereof and further adapted to project through the body of the other sleeve for connecting the handle sections together, and one of said sections provided with means to form a clearance for the operation of said latching means, and one of said sections having a tongue and the 95 other a socket for the reception of the tongue when the sections are connected together. 100

In testimony whereof I affix my signature in the presence of two witnesses.

FRED A. HAUSE.
